FOREIGN PATENT DOCUMENTS

WO 2009/070313 A1 6/2009

Primary Examiner — Garth Rademaker*Assistant Examiner* — Samantha Q Lawrence(74) *Attorney, Agent, or Firm* — Zeman-Mullen & Ford, LLP(57) **CLAIM**

The ornamental design for an imaging booth, as shown and described.

DESCRIPTION

FIG. 1 is a perspective view of an imaging booth showing the present invention;

FIG. 2 is a bottom perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top view thereof;

FIG. 8 is a bottom view thereof;

FIG. 9 is a front perspective view of the imaging booth showing the front door panels in an open position;

FIG. 10 is a bottom perspective view thereof; and,

FIG. 11 is an elevational view of the imaging booth showing the front door panels in an open position and the side doors in an open position.

The broken lines shown in FIG. 2 and FIGS. 8-11 illustrate portions of the imaging booth that form no part of the claimed design.
